GEORGE H. PIERCE AND MARTIN T. GLIMSETAL, OF MINERAL POINT, WISCONSIN.

Letters Patent No. 79,079, dated June 23, 1868.

IMPROVED EXTENSION-TRESTLE OR HORSE.

The Schedule referred to in these Letters Patent and making part of the same.

TO ALL WHOM IT MAY CONCERN:

Be it known that we, GEORGE H. PIERCE and MARTIN T. GLIMSETAL, of Mineral Point, in the county of Iowa, and State of Wisconsin, have invented new and useful Improvements in Extension-Horses or Trestles; and we do hereby declare that the following is a full, clear, and exact description thereof, which will enable others skilled in the art to make and use the same, reference being had to the accompanying drawings, forming part of this specification.

Figure 1 is a side elevation of our improved extension-horse.

Figure 2 is an end elevation of the same.

Figure 3 is a cross-section of the same through x x , fig. 1.

Figure 4 is a view similar to fig. 1, but extended.

Figure 5 is a horizontal section of the legs, taken through the line y y , fig. 2.

Figure 6 is a detail view of a clamp for the legs.

Figure 7 is a sectional view of the trestle when folded for transportation.

Figure 8 is a detail view of the notch-device.

Similar letters of reference indicate corresponding parts.

This invention relates to a portable trestle-horse, for scaffolding and other purposes, and consists of elevating and extension-devices, which will hereinafter be more fully set forth.

The general points of the invention are shown by the drawings, and consist of a trestle or horse, composed of upper legs, A, which work with sliding contact upon the extension-legs A', the legs A being bolted to horizontal extension-girders D and D' by a bolt and nut, as shown at r , and will be further described at the proper connection.

We will first set forth the elevating-mechanism, by means of which the height of the trestle is increased or diminished.

The legs A and A' slide by each other within iron bands n and n' , the said bands being screwed or bolted to the legs A, and thus provide a means of holding the legs firmly by the lapped parts or doublings of the same.

The legs and elevating-devices of the same being alike at both ends of the trestle, we describe minutely only one end.

An elevating-screw, G, has its upper bearing on the end of the extension-girder D or D', as shown. The lower bearing is shown at d' , it being a lug projecting from the cross-brace i' , (best shown at fig. 5,) and through a hole in this lug the reduced end, g'' , of the screw G projects, the said lug acting simply to steady the screw.

An upper cross-bar, i , is provided with a hollow screw, fitting the thread of G, and reduced ends or arms j , which rest in hooks, f , fixed firmly to the upper ends of the legs A', as shown.

A collar and washer, s and s' , are on the upper part of the screw G, to bear against the girder D at that point, and transmit the thrust of the screw to the upper parts of the trestle.

The screw projects through a hole in the platform-plank B, and terminates in a square arbor, g , on which fits a crank, g' , for turning the screw when the platform is to be elevated or lowered; for, as will be evident, when the said screw is turned to elevate the platform B, the hollow screw in the cross-bar i , being held stationary thereby, causes the screw to be elevated, and with it the upper parts of the horse, to which the platform is attached, by the collar and washer, s and s' , impinging against the girder D.

When the platform is to be lowered, the screw is turned reversely, and the platform and legs A, attached thereto, descend by their own weight as the screw is turned. The same action obtains at the other end of the trestle when the screw of that end is turned in like manner.

The lateral extension of the trestle and platform requires no mechanism to actuate it in being extended, but is simply grasped by the legs, or other convenient parts, and drawn away laterally. This extension is permitted by devices now to be described.

The legs A of either end of the trestle are bolted to a girder, D or D', by the bolt r, as shown.

These two girders work parallel and in lateral contact with each other, and their surfaces of contact are provided with a tongue-and-groove device, the groove e' extending from the bolt r to the commencement of the slot e in the girders. A short tongue at the end of each girder fits in the slot of the corresponding girder.

The slot e is formed in each girder, about half its length from the inner end of the girder, and is for the purpose of permitting the presence of the bolt r', which holds the girders together, and, at the same time, forms the base and support of the central brace a', by which the platforms B B' are held together, and yet permitted to slide in easy contact past each other.

This brace a' is shown in section at fig. 3. The lower ends of the brace are held by the bolt r', which passes through slots in the said ends, the nut and head of the bolt serving to keep the slotted ends of the brace closely against the girders when the same are clamped by the bolt-nut.

A guide, a'', is riveted or otherwise attached firmly to the brace a', and acts as a guide to hold the planks B B' together, while permitting them to slide freely.

The braces a, at the ends of the trestle, are secured by the bolts r, as shown. The planks are bolted or otherwise fastened to the horizontal part of the end-braces a, but the middle brace, a', is free to move horizontally with the passage of the bolt r' (to which it is attached) in the slots, e, of the guides, thus conducing to the free extension of the trestle.

Diagonal braces, h, confer rigidity and firmness to the wooden parts of the trestle proper. These braces rise from the cross-pieces i', into which they are hooked by means of the slots in the cross-piece and hooked part b, as shown at fig. 5.

Rising thence, they cross each other, and their upper ends are held in plates m, the ends of the braces being turned to form an eye or knuckle, which fits into a corresponding cavity in the said plates m, as this form of connection will permit the required vibration of the rods when the trestle is to be brought into a smaller compass, requisite for portability.

The plates m are bolted to the under side of the girder to which they belong, respectively.

A short chain, terminating in a ring, is attached to each of the bolts r by an eye on the screw-end of said bolts, and are for the purpose of preserving the nut and washer from loss or misplacement when the trestle is being reduced in compass. It also permits the complete separation of the legs A from the girders in like case.

When the trestle is to be reduced in compass, and thereby made more portable, it is accomplished by unscrewing the nuts from the bolts r, and unhooking the braces h from the cross-bars i', and unhooking the cross-bar i from the hooks f, which can be accomplished when the legs A are loosely hanging by the chains and rings aforesaid, for the screw-ends g'' can then be lifted from the lugs d, and the screws withdrawn from their upper bearings. The cross-bars i' are also unhooked from one side, where they have bent ends, which catch in eye-bolts, or their equivalent. The other ends are provided with an eye, which is linked with another eye-bolt, or its equivalent. This arrangement is shown at fig. 2, and is for the purpose of permitting the disconnecting of the adjacent parts, when the trestle is to be taken down and folded.

The trestle is then closed up laterally, and the legs and other parts folded as shown in figure, being thus in a convenient portable form, as shown at fig. 7.

The eccentric-clamp, shown at fig. 6, is for the purpose of attaching additional legs to the legs A' when it is required to elevate the platform higher than the legs A' will permit. This clamp consists of a band, k, for clamping against the socket H two strengthening-strips, p, the said socket being of metal, and containing the abutting ends of the leg A' and a supplementary leg, A''.

The ends of the band k terminate in hooks, as shown, in which hooks the reduced ends of the eccentric-clamp roller v are held. A handle, v', forms part of the clamp-roller, and the latter is operated by it in the usual manner.

The upper ends of the legs A are notched, as shown, and fit on a corresponding notch in the ends of the girders, as shown at fig. 8. This device is for the purpose of preventing the legs from working down when sustaining the thrust of the screw G in elevating the platforms.

The hooks f may be attached in several ways to the legs A'.

In fig. 1, one hook is shown attached to the end of the leg, and the other is hooked over a metallic band, f', as shown.

In fig. 2, another modification of the hook is shown. This is attached to the end of the leg by a staple, f'', and is movable.

The invention is designed as an improvement on one previously patented by one of the present applicants, and while being simple, cheap, and durable, is easily operated, and conducive to the perfect working of a portable trestle or horse for scaffolding or other purposes.

We claim as new, and desire to secure by Letters Patent—

1. The travelling-boards B B', constituting the platform of trestle or horse, substantially as shown and described, in combination with the braces a a' and their respective bolts r r', all as and for the purpose set forth.
2. The screws G, in combination with the cross-bar i and the hooks f, substantially as shown and described, and for the purpose specified.
3. The slotted girders D D', in combination with the legs A, platforms B B', and bolt r', substantially as shown and described, and for the purpose specified.
4. The plates m, substantially as shown and described, in combination with the braces h and the slotted girders D D', all as and for the purpose set forth.

5. The cross-bars *i*, substantially as shown and described, in combination with the legs *A*, braces *h*, and slotted girders *D* and *D'*, all as and for the purpose set forth.
6. The cross-bars *i*, substantially as shown and described, in combination with the screw *G* and legs *A'*, all as and for the purpose set forth.
7. The brace *a'*, when combined with a guide, *a''*, and bolt *r'*, all constructed and operating substantially as shown and described, and for the purpose specified.
8. The hooked and hinged cross-bar *i'*, substantially as shown and described, in combination with the legs *A*, slotted girders *D D'*, and platform *B B'*, all as and for the purpose set forth.
9. The chains *g*, in combination with the bolts *r* and legs *A*, all substantially as and for the purpose shown and described.
10. The notches in the legs *A*, in combination with a corresponding notch on the girders, and the screw *G*, all substantially as shown and described, and for the purpose specified.
11. The clamp-device, consisting of the metallic strap *k* and eccentric-roller *v*, substantially as shown and described, in combination with the legs *A'* and supplementary legs *A''*, and strips *p*, all as and for the purpose set forth.
12. The tongue and its groove *e'*, in combination with the girders *D D'*, substantially as shown and described, and for the purpose specified.

GEORGE H. PIERCE,
MARTIN T. GLIMSETAL.
